CLAIM

The ornamental design for a shoe sole, as shown and described.

DESCRIPTION

FIG. 1 is a left side view of a shoe sole in accordance with our new design;

FIG. 2 is a right side view thereof;

FIG. 3 is a front view thereof;

FIG. 4 is a rear view thereof;

FIG. 5 is a top view thereof; and,

FIG. 6 is a bottom view thereof.

The dashed-dashed-dashed lines shown in the figures depict portions of the shoe sole that form no part of the claimed

(Continued)

design. The dashed-dot-dashed lines indicate a boundary between the claimed portions and the unclaimed portions of the design.

1 Claim, 5 Drawing Sheets
